UNITED STATES PATENT OFFICE.

CHARLES STEWART FORBES, OF STRATHDON, SCOTLAND.

ACETYLENE-GAS-GENERATING LAMP.

SPECIFICATION forming part of Letters Patent No. 617,780, dated January 17, 1899.

Application filed July 11, 1898. Serial No. 685,696. (No model.)

To all whom it may concern:

Be it known that I, CHARLES STEWART FORBES, ¹ a subject of the Queen of Great Britain, residing at Castle Newe, Strathdon-by-Aberdeen, Scotland, have invented certain new and useful Improvements in or Connected with Acetylene-Lamps; and I do hereby declare the following to be a full, clear, and exact description of the invention, such as will enable others skilled in the art to which it appertains to make and use the same.

My invention relates to improvements in or connected with self-generating acetylene-lamps, the objects I have in view being to produce a regular and steady supply of gas with the least evolution of heat from the decomposition of the calcium carbid by the action of water in the generator and to enable the light given by the lamp to be regulated or extinguished at will, the construction of the apparatus also being such as to permit of the ready removal for cleaning or otherwise of the principal operative parts. I attain these objects by the mechanism illustrated in the accompanying drawings, in which—

Figure 1 is a vertical sectional elevation of a complete lamp and generator. Fig. 2 is an enlarged sectional view of a modification: Fig. 3 is a sectional view of part of a dripping-tube on an enlarged scale. Fig. 4 is a plan of the cover.

In the drawings (see Fig. 1) I have shown a complete lamp and generator suited for table use. The cistern 1 and its top 1^a and bottom 1^b, the generator 12, stem 1^c, and foot 1^d may be cast in metal, such as brass, or they may be spun or otherwise formed in any suitable metal, such as brass or iron plate, the respective parts being subsequently soldered or screwed together.

All the parts of the apparatus exposed to action of the acetylene gas should be tinned.

The top of the cistern 1^a is headed, as at 5, and fitted with a screwed cap or cover 2, rubber packing 16 being employed to make the joint. This cap is fitted with wings 2^b for the purpose of screwing it on or off. It is threaded on its upper part 5 and fitted with a gas-cock 6, nipple 7, and shade-holder 8. A tube 9, threaded near its lower end at 5^a and packed with a washer 16^a, is screwed into the bottom of

cistern 1^b and rises nearly to the top of the gas vessel 4, which is soldered into the cap 2. At a suitable point the tube 9 is drilled diagonally, as at 10, the hole threaded, as at 5^b, and into this hole is screwed a dripping-nozzle 10^a, which is perforated with a very fine hole 10^b, the head being nicked screwwise 10^c, so that it may be put in or removed with a screwdriver. I may drill and tap the tube 9 at several points, (see Fig. 3,) so that the height of the nozzle, and consequently the pressure upon the gas, due to the head of water in the cistern, may be varied by interchanging the nozzle 10^a with one or the other of the screwed plugs 10^d. I usually form the head of the tube 9 of hexagon or other suitable shape 9^a, so that it may be screwed into or out of the base by means of a spanner or key. Part of the base of tube 9 is cut away, as at 9^b, so as to prevent any accumulation of water and to compel that flowing through the nozzle 10^a to fall in drops.

In the top of the cistern a filling-tube fitted with a screwed cap 2^a, perforated at 3, is inserted, and to prevent the ignition within the cistern of any acetylene gas escaping as the result of overproduction I line the base of the opening or tube with gauze 2^c. The base of the cistern 1^b is threaded, and to this is screwed the generator 12, the joint being made with rubber packing 16. I prefer to load the foot 1^d with lead to insure steadiness.

The operation of this first form of my invention is as follows: The generator 12 is unscrewed, charged with carbid of calcium, and replaced. The screwed cap 2^a is removed and water poured into the cistern 1. Since the gas vessel 4 is full of air or gas, as the case may be, the water is prevented from rising in it until the cock 6 is turned on. The water then rises until the dripping-nozzle 10^a is covered and falls in drops upon the carbid beneath, thereby liberating acetylene gas, which rises through the tube 9 and into the air vessel 4, thus supplying the burner. If the cock be partially closed or if gas be generated in excess of the demand, the pressure in the gas vessel increases and the head of water is lowered, so as to be below the nozzle, when the further generation of gas ceases.

and that the particular shape of the end of the tube 9^b prevents the water from flowing in upon the carbid, except in the form of drops.

- In Fig. 2 I have shown a modification in which the dripping-tube 9 is inserted by screwing into the base of the cistern 1. This cistern is divided by means of a diaphragm 17 in the manner shown, the only opening for the flow of water into the lower compartment being through the depending tube 20. It will be seen that the gas vessel 4 unites the diaphragm with the screwed cap 2 and that as a consequence the capacity of the gas vessel may upon a sudden liberation of gas be automatically increased; but since the aperture by which the water enters is of small area its rise and fall is less in proportion to its displacement, which has the effect of producing a steadier flame.
- Although I have described my improvements as applicable more particularly to table-lamps, I do not confine myself to such, as they may be used for many varying types.
- Having thus fully described my invention, what I claim, and desire to secure by Letters Patent, is—
1. In combination with a water-receptacle and a gas vessel communicating with the interior thereof, a generator adapted to contain carbid of calcium and arranged below the said receptacle and a tube extending from the said generator up into the said gas vessel and provided with a lateral water-inlet in order that it may serve for the downward pas-

sage of water to the carbid as well as for the upward passage of gas, substantially as set forth.

2. A tube provided in its side with screw-threaded holes at different heights and with plugs and a nozzle adapted to fit the same for adjusting vertically at will the point of water-inlet of the said tube, in combination with a generator adapted to contain carbid of calcium and to receive the dripping from the said tube, a water-cistern and a receptacle for the gas generated by the action of the water on the carbid, there being communication between said cistern, said gas-receptacle and said tube, substantially as set forth.

3. In combination with a water-cistern divided horizontally by a diaphragm, and provided with a removable cap, a gas vessel attached to said cap for removal therewith and communicating with the cistern below the diaphragm, means of communication between the upper and lower parts of the interior of the said cistern through the said diaphragm, a tube making communication between the said vessel and the said generator, and a nozzle making communication below the diaphragm between the said cistern and the said tube, substantially as set forth.

In testimony whereof I affix my signature in presence of two witnesses.

CHARLES STEWART FORBES.
